Primary Examiner — T Chase Nelson*Assistant Examiner* — Jeff Lenard D Torres(74) Attorney, Agent, or Firm — Banner & Witcoff, Ltd.CLAIM

The ornamental design for a shoe, as shown and described.

DESCRIPTION

FIG. 1 is a bottom front perspective view of a shoe showing my new design;

FIG. 2 is a bottom view thereof; and,

FIG. 3 is a bottom rear perspective view thereof.

The broken line showing of the two racetrack shaped regions form no part of the claimed design. The broken line showing of the eleven small circular shaped regions form no part of the claimed design. The broken lines depicting the remainder of the shoe form no part of the claimed design.
